UNITED STATES PATENT OFFICE.

RASMUS M. HVID, OF CHICAGO, ILLINOIS, ASSIGNOR TO R. M. HVID COMPANY, OF CHICAGO, ILLINOIS, A CORPORATION OF MICHIGAN.

VALVE FOR HYDROCARBON-ENGINES.

1,346,204.

Specification of Letters Patent. Patented July 13, 1920.

Application filed May 24, 1918. Serial No. 236,319.

To all whom it may concern:

Be it known that I, RASMUS M. HVID, a citizen of the United States, and resident of Chicago, in the county of Cook and State 5 of Illinois, have invented certain new and useful Improvements in Valves for Hydrocarbon-Engines, of which the following is a specification.

My invention relates to hydro-carbon engines and particularly to a novel needle valve controlling device for use in connection therewith.

My improvement is intended primarily for use in connection with an engine of the Hvid 15 type in which liquid fuel is inhaled on the suction stroke of the engine although it may be employed to advantage in other types of engines. In an engine of the type described, the fuel is supplied through a suitable con- 20duit to an ignition cup located in the compression space of the cylinder, the quantity of fuel being controlled by a suitable needle valve. The time of admission of the fuel and a small quantity of air to the cup is com- 25monly controlled by a puppet valve actuated by a cam shaft in the usual manner.

The speed and the power of the engine must be controlled by regulating the position of the needle valve and this is usually 30 accomplished by a governor acting through suitable connections to raise or permit the lowering of the valve. In the constructions heretofore proposed the needle valve is projected through the valve casing the escape 35 of fuel being prevented by packing the joint. Inasmuch as the fuel is usually under more or less pressure this necessitates a relatively tight packing and the valve is moved with the expenditure of more or less force. 40 Usually the valve is moved in one direction by a spring and in the other direction, in opposition to the spring, by the governor. Where the packing gland is relatively tight, the spring must be of such strength 45 as to readily move the valve and this results in more or less irregularity in speed. However, if the packing should become too tight, the valve is liable to stick in an open position resulting in the racing of the engine.

An object of this improvement is to so mount the needle valve that no packing is required. Regulation of speed may therefore be much finer and the dangers heretofore referred to are avoided.

Another object is to simplify and improve the form of connection between the governor-actuated element and the valve. In constructions heretofore employed the position of the valve has been controlled by a 60 rocker or forked arm engaging the head of the needle valve, the parts being located exteriorly of the engine. Such parts were not infrequently damaged by rough handling and the regulation thereby became uncer- 65tain. In the construction here proposed there is in effect a floating needle valve the valve being entirely incased or inclosed, a projection therein being adapted to contact with the notched portion of a stub shaft 70 suitably mounted in proximity thereto. The mere rotation of the shaft therefore has the effect of controlling the position of the valve and all the parts are inclosed. In practice it may be unnecessary to employ a spring 75 for seating the needle valve the same being so loosely held in the space as to enable it to seat by gravity.

The invention will be more readily understood by reference to the accompanying 80 drawings, wherein:

Figure 1 is a vertical section partly in elevation, showing the application of my device to a hydro-carbon engine;

Fig. 2 is a plan view of the casing and 85 connections, and,

Fig. 3 is a vertical sectional view on the irregular line 3—3 of Fig. 2.

In the drawings it will be seen that the engine may include a cylinder 10, and piston 90 11, the valves and means for ignition being contained within the head 12. Suitable valves, one of which is indicated at 13, are provided for the admission of air and the escape of burned gases. These valves are 95 actuated by rockers 14, controlled by a push-rod 15, in the usual manner.

The ignition means comprise the casing 16, to which liquid fuel is supplied through the pipe 17, the pipe terminating in a conduit 18, having a valve seat 19, at the lower end thereof. The conduit terminates in a seat 20, having a puppet valve 21, controlled by a stem 22, and normally held in closed position by the spring 23. This valve is 105 opened with the air intake valve by being contacted at the point 24, by the rocker 14. As the valve 21, is opened, a quantity of fuel and a small quantity of air are admitted to the cup 25, which is in commun- 110

2
cation with the compression space by one or more minute apertures 26. The quantity of fuel admitted is controlled by the needle valve 27, which coöperates with the seat 19, 5 and occupies the conduit 18. A space 28, is provided which is in communication with the conduit. Within this space the upper end of the needle valve is accommodated, this upper end being provided with a collar 10 29, which forms a support for the coil spring 30, contained within a threaded cap 31, which closes the entrance to the space 28. The collar is also engaged by the segmental edge of a shaft 32, which projects 15 into the casing and forms a bearing in a recess therein. The shaft, as shown in Fig. 2, is packed by means of a gland nut 33, the shaft terminating in a crank 34, which may be connected to suitable automatic or manual governing means as desired. A governor is indicated at 35 which is adapted to actuate the arm 34, suitable connections 36 being provided for that purpose. It will be noted that in order to provide 20 the segmental portion of the shaft the same is notched at the point of engagement with the needle valve.

By providing a shaft of suitable size, the required lift of the valve may be secured 30 and as the controlling crank 34, may be of any desired length, the governing action may be finally adjusted. The important advantage, however, is that the needle valve is not packed or restrained in any manner 35 and even though the spring 30, should become broken, the valve would seat by the combined action of gravity and the suction developed on the intake stroke of the piston.

Obviously the manner of mounting the 40 needle valve and the means for securing the desired result may be varied without departure from the spirit of my invention.

I claim:

1. In an oil engine, the combination of 45 a valve casing, a fuel cup on the lower end thereof, a puppet valve for controlling the time of admission of liquid fuel and a small

quantity of air to said cup, said casing providing an inclined passage terminating at 50 said puppet valve, a cap for closing the upper end of said passage, a governor-controlled needle valve contained in the passage, said valve being provided with an annular flange near its upper end, a spring 55 engaging said flange, a shaft projecting into the casing and having a portion engaging said flange, and means for packing said shaft at the point of entrance thereof to the casing, substantially as described.

2. In a hydro-carbon engine, the combination of means for supplying fuel, a governor-controlled needle valve for controlling the quantity of fuel supplied, said needle valve having a projection at a point 60 in the length thereof, a notched shaft located adjacent to the needle valve, the projection on the needle valve being located in the notch in the shaft whereby the position of the valve is controlled by the rotation of the shaft, substantially as described. 65

3. In a hydro-carbon engine, the combination with a cylinder, of an igniting unit comprising a body adapted to be inserted into a recess in the cylinder, a fuel cup carried by said body, a conduit in said body 70 for conducting liquid fuel to said cup, a governor-controlled needle valve mounted in said conduit, said needle valve having a flange, a spring engaging said flange, a cap screwed into the body and serving to 75 close the fuel passage and to support said spring, and a notched shaft also mounted in said body in such position that the flange on the needle valve engages said notch, the parts being so arranged that upon oscillation of said shaft the needle valve is caused to be reciprocated, substantially as described. 80

Signed at Chicago, Ill., this 22nd day of May, 1918.

RASMUS M. HVID.
